Primary Examiner — Kendra Leslie Hamilton(74) *Attorney, Agent, or Firm* — Dickinson Wright PLLC; Andrew D. Dorisio(57) **CLAIM**

The ornamental design for a mold for an ungulate shoe, as shown and described.

DESCRIPTION

FIG. 1 is a top, rear, left perspective view of a mold for an ungulate shoe, showing our design;

FIG. 2 is a bottom, front, right perspective view thereof;

FIG. 3 is a top plan view thereof;

FIG. 4 is a rear elevation view thereof;

FIG. 5 is a front elevation view thereof;

FIG. 6 is a bottom plan view thereof;

FIG. 7 is a left side elevation view thereof;

FIG. 8 is a right side elevation view thereof; and,

FIG. 9 is a left side cross-sectional view of the mold for an ungulate shoe of FIG. 1, taken in the direction of line 9-9 of FIG. 4.

The broken line depictions form no part of the claimed design.

1 Claim, 4 Drawing Sheets(56)
